UNITED STATES PATENT OFFICE.

ALFRED SIEBERT, OF NEW YORK, N. Y.

HAND-STAMP.

SPECIFICATION forming part of Letters Patent No. 469,277, dated February 23, 1892.

Application filed February 11, 1889. Serial No. 299,378. (No model.)

To all whom it may concern:

Be it known that I, ALFRED SIEBERT, of the city and county of New York, in the State of New York, have invented a certain new and 5 useful Improvement in Hand-Stamp, of which the following is a specification.

My stamp may have a handle for the application of the force directly, or it may be connected by levers or otherwise to any suitable 10 mechanism for operating it. I will show it with a simple handle. There are removable types and means for fastening and liberating them. I will show a screw. I finish the periphery of the main portion to receive an 15 obliquely-mounted ring, and I provide such a ring with recesses for type and screws or other convenient means for holding such, distributed equally or unequally around the periphery. The ring is so placed and the types are 20 so arranged therein that only one of the words or devices mounted in the oblique ring will be presented at any one time to receive the ink and to effect the stamping. The others all remain idle. The ring is partially re- 25 volved to carry any word out of use and to bring another one into the place for printing. The upper or back face of the ring is marked with the same word as the types or other printing device on the face or with some 30 other word or number which the operator should learn. This greatly aids in setting the ring to print the required word or device. There is, furthermore, a notch on the upper 35 face of the ring corresponding to each word. This is engaged by a spring carried on the main part. It insures that the ring when once adjusted shall remain firmly in the required position until it is intentionally shifted.

The accompanying drawings form a part of 40 this specification and represent what I consider the best means of carrying out the invention.

Figure 1 is a plan view. Fig. 2 is a central vertical section, and Fig. 3 is a side elevation.

45 Similar letters of reference indicate corresponding parts in all the figures where they occur.

A is the main body of the stamp, certain 50 portions being designated when necessary by supernumerals, as A'. The lower face A' is recessed to receive one or more series of re-

movable types a. They are confined and released at will by a screw or screws B. A portion A² of its periphery is turned or otherwise produced in a circle standing oblique to the plane of the faces of the types a and consequently standing oblique to the paper or other surface upon which the stamp is to be used. The periphery A² is grooved, as shown. A follower C is screwed upon the correspondingly-inclined surface above and forms a removable portion of the main body. The portion A² of the main body, with the follower C, forms a bearing for a ring D, which is capable of being shifted around. Its lower face 65 is recessed and receives removable types d, which are secured by screws E. Its upper face is notched, as indicated by d'. A locking-spring G, mounted on the main body, is adapted to engage in the notches successively 70 as they are presented under it and to hold the ring firmly in the position to allow the corresponding type d to produce its impression by the side of and jointly with the types a. The notches d' should be beveled, so that 75 when sufficient force is applied, tending to turn the ring D, the spring will yield of itself and allow the ring to be turned; but the sides should be sufficiently steep and the spring should have sufficient force to hold the ring 80 reliably in place against the slight disturbing forces to which it will be subjected when in use.

My ring may be shifted with great facility 85 to change the words which are printed alongside of the removable types. Thus if the latter carry the day the removable ring may carry the words "Shipped," "Entered," "Seen," "Answered," "Paid," "Referred," "Attended to," or the like. Either of these may be 90 brought into position for work by a single simple movement. The oblique position allows only one of the words to come into use at any one time.

Modifications may be made without departing 95 from the principle or sacrificing the advantages of the invention. I can print other devices than words by means of my ring D. The devices d to effect the printing may be engraved or otherwise produced on the lower 100 face of the ring D, instead of employing removable types. In such case the screws E

may of course be omitted. The obliquity of the bearing-surface A² and of the rings C and D allows a large ring D to be used without coming in the way of the hand or necessitating any material increase in the height of the device. I can use a greater or less number of words or other devices on the ring D.

Parts of the invention can be used without the whole. The arrangement allows movable type to be used in the main part A; but the printing devices a may be of rubber or other suitable material and may, if preferred, be formed in one piece with the body A, or attached immovably thereto, if preferred.

I do not claim the obliquely-mounted ring, except when provided, as shown, with means for holding it in predetermined position.

I disclaim the combination, in a hand-stamp, of a ring mounted on an oblique bearing-surface and carrying printing devices, either of

which may be brought instantly into position for use with a main body, and printing devices fixed therein and arranged for joint operation.

I claim as my invention—

In a hand-stamp, the notched ring D d', mounted on the oblique bearing-surfaces A² C and carrying printing devices d, in combination with the main body A and printing devices a carried therein, and with the locking-spring G, all arranged to serve substantially as herein specified.

In testimony whereof I have hereunto set my hand, at New York city, this 1st day of February, 1889, in the presence of two subscribing witnesses.

ALFRED SIEBERT.
